UNITED STATES PATENT OFFICE

2,564,265

WINDOW

Frank W. Knott, Weslaco, Tex., assignor to Wisco, Inc., Detroit, Mich., a corporation of Michigan

Original application February 12, 1947, Serial No. 728,171. Divided and this application December 27, 1949, Serial No. 135,261

1 Claim. (Cl. 20—11)

1

The present invention relates to window frame construction and more specifically to the sash holding and guiding portion thereof.

It has among its objects the provision of means by which sash may be easily removed if desired, for cleaning or any other purpose.

Other objects will readily occur to those skilled in the art upon reference to the following description and the accompanying drawings in which:

Fig. 1 is a view in elevation of a window frame including the present invention.

Fig. 2 is a section on line 2—2 of Fig. 1 with part broken away.

Fig. 3 is a section on line 3—3 of Fig. 1.

Fig. 4 is a view in elevation of a portion of the removable guide rail as viewed from line 4—4 of Fig. 3.

Fig. 5 is a view on line 5—5 of Fig. 3.

Fig. 6 is a partial view in elevation of a window including a modification of the invention.

Fig. 7 is a section on line 7—7 of Fig. 6.

Fig. 8 is a sectional view showing the operation of the latter.

Fig. 9 is a section on line 9—9 of Fig. 8.

Fig. 10 is a detail in perspective of a portion of Fig. 7.

The window frame as shown in Fig. 1 is, as is conventional, a rectangular frame, but in the present construction, is made up of outwardly open channel members 14 and 15 of which the side members 15 (see Fig. 2) are so formed as to provide a deep channel opening outwardly and a shallow channel 15B opening inwardly of the frame. Adjacent the channel 15B this inward face of member 15 is also provided with a flange 15C the purpose of which will appear later.

Mounted in the channels 15A are other channel members 16 opening inwardly and these constitute the outer margins of the completed frame, the construction of which is described in detail and is being claimed in application Serial No. 728,171, filed February 12, 1947, by the present inventor on "Window" and of which the present application is a division.

As indicated in Figs. 1 and 2, carried in channels 15B in members 15 in a sash guide strip 17, this being shown as E-shaped in section with its ribs 17A or flanges projecting outwardly from member 15. These ribs 17A serve as guides for the slideable sash 18 and 19, the sash being provided with grooved side members 18A and 19A adapted to embrace the ribs and slide thereon. The flange 15C, mentioned above, serves as sealing guide member for the sash 18 arranged at

2

the outer face of the window. The grooves in side members 18A and 19A loosely receive the ribs 17A, and the two outer sashes 18 are pressed inwardly in any suitable manner against the middle sash 19 as shown in Fig. 2, for example, to seal the joints between the respective sashes.

The sash 18 and 19 are shown as glass panelled and screen panelled respectively.

As best shown in Figs. 3 and 8, the guide strips 17 are each in two parts, an upper 17B and a lower piece 17C in alignment therewith. The upper piece 17B is permanently fixed in position in the channel 15B while the lower piece 17C is so arranged as to be removable or tilted (as in Figs. 6 to 10).

In Figs. 3, 4 and 5, the piece 17C of the sash guide is shown as being prevented from lateral displacement by its location in a channel 15B and by being notched at its bottom as at 17D to fit over a sealing rib 20 carried by the horizontal bottom frame member 14, and is held within the channel 15B and against vertical movement by a pin 17E fixed to the rear surface of the piece 17C and extending through a suitable opening in the side member 15, the head 17F of the pin engaging a spring holding means 17G.

In the modification shown in Figs. 6 to 10, side frame member 115 is shown as having a plane face 115A but provided with the flange 15C, while the lower part 117C of the sash guide is of the same width as the plane face 115A and is arranged to swing outwardly from the top as indicated in Fig. 7, the two parts 117C being connected and operated by a suitable handle 120 if desired. Further, in order to limit such movement and provide added means to prevent horizontal movement, these parts 117C are preferably provided with a suitable button member 121, passing through a slotted opening 122 in member 115.

At the upper ends of parts 117C a suitable catch 130 for preventing the swinging movement may be provided. Such a catch as shown in Figs. 6, 7 and 10, the catch itself being shown in Fig. 10 as consisting of a small plate provided with a finger piece 130A and an L-shaped flange 130B adapted to slide in suitable grooves in the part 117C and the upper fixed part 117B of the sash guide. When the flange 130B is partially in each groove, of course, the part 117C can not swing.

In the operation of the present invention, as shown in either form, if all of the sash are fully "up," the lower movable part of the sash guide rail may be moved out of guide position and the

sash then removed at will. Or, depending upon the dimensions of the several parts, in the form shown in Figs. 6 to 10, all of the sash may be in full "low" position, and all may then be tilted out with the swinging guide portions 117C.

I claim:

In a window, an upright rectangular frame, opposed vertical guide rails fastened to said frame at opposite sides thereof, each of said guide rails having a plurality of laterally spaced, inwardly extending ribs and corresponding ribs of the guide rails being aligned with each other, a plurality of sashes mounted in the frame for vertical sliding movement on the guide rails, inwardly extending flanges on the frame at opposite sides thereof overlapping one of said sashes and providing a weather seal between the sash and the frame, each sash having vertical grooves in the side edges thereof, the width of the grooves be-

ing greater than the thickness of the ribs to provide an essentially loose fit between the outermost sash and the ribs on which it travels.

FRANK W. KNOTT.
